FURNACE DOOR FRAME

Ottwin L. Braun, Pittsburgh, Pa., assignor to Reliance Steel Products Company, McKeesport, Pa., a corporation of Pennsylvania

Application May 12, 1953, Serial No. 354,590

3 Claims. (Cl. 122—499)

This invention relates to water-cooled furnace door frames and, more particularly, to an improved construction which eliminates warping or toe-in of the frame legs upon cooling after removal of the frame for furnace repairs.

Water-cooled furnace door frames for open-hearth furnaces and the like are conventionally fabricated from pressed and welded steel plate and have a water-containing body portion forming the top of the frame and two hollow depending legs opening into the top and forming the sides of the frame. The legs and top of the frame are formed of front and rear plates which are joined together in spaced relation by top and side plates welded to their outer edges. An arch-bar joins the inner edges of the front and rear plates to complete the water-containing enclosure of the frame. The arch-bar defines the opening into the furnace and is continuously and directly exposed to the furnace heat. When the frame is removed to make furnace repairs, the legs frequently warp or toe-in to an extent that their lower ends are not receivable in the recesses provided in the metal fore-plate or sill carried by the breast-plate. Before the frame can be re-installed in the furnace, the legs must be straightened and this is a difficult and time-consuming operation which commonly increases the furnace shut-down time.

One of the principal objects of this invention is, as indicated, to provide an improved furnace door frame construction which will eliminate warping or toe-in of the frame legs upon cooling. To this end, the interior surfaces of the frame legs in the vicinity of the arch-bar are provided with metal heat conductors which are integrally connected by welding with the metal plates forming the frame. In the preferred embodiment of the invention, the heat conducting elements are in the form of pins welded to the internal surface of the arch-bar and to the internal surfaces of the front and back-plates adjacent the arch-bar. The invention also contemplates the use of heat conducting metal plates in place of plural pins. The pins or plates extend into the path of movement of the cooling water flowing through the legs and transfer heat to the water from the arch-bar. In this manner, excessive heating of the arch-bar is prevented, and toe-in of the legs is eliminated upon cooling of the frame after removal from the furnace. The invention thus eliminates the troublesome and costly leg straightening operations heretofore required and reduces the furnace shut-down time when repair is required.

Other objects and advantages of the invention will become apparent from the following description.

In the drawings, several embodiments of the invention are shown. In this showing:

Fig. 1 is an elevational view of a water-cooled furnace door frame illustrating a preferred embodiment of the invention;

Fig. 2 is a sectional view taken substantially along the line II—II of Fig. 1;

Fig. 3 is a top plan view of the frame shown in Fig. 1;

2

Fig. 4 is a sectional view taken along line IV—IV of Fig. 1;

Fig. 5 is a fragmentary front elevational view of one leg of a frame illustrating a modified embodiment of the invention;

Fig. 6 is a side view of the leg shown in Fig. 5;

Fig. 7 is a sectional view taken substantially along the line VII—VII of Fig. 5;

Figs. 8, 9 and 10 are views respectively similar to Figs. 5, 6 and 7 illustrating a modified form of the invention; and

Figs. 11, 12 and 13 are views respectively similar to Figs. 5, 6 and 7 illustrating a further modified form of the invention.

15 In the drawings the numeral 1 designates as a whole a hollow water-cooled frame for a furnace doorway. The top 2 of the frame is a hollow water-containing body portion having legs 3 internally communicating therewith and depending therefrom in laterally-spaced relation and

20 forming the sides of the frame. Water is supplied to the interior of the frame through a supply conduit 4 to a manifold 5 having nozzles 6 for directing water into a nose or lintel 7 for protecting the usual skewback channel of the furnace (not shown). The ends of the manifold 5 are connected with vertically-extending conduits 8 which supply water to the bottom portions of the legs 3. The path of movement of the cooling water through and its exit from the frame 1 is substantially as shown and described in Patent No. 2,427,547 issued September 16, 1947, to

30 W. C. Bulmer and will not be repeated here.

The frame 1 is formed of pressed and welded steel plate in a conventional manner and includes an arch-bar 9. The arch-bar 9 is a flat steel plate shaped to the form of an inverted U having a horizontal portion 10 and 35 depending end portions 11. The arch-bar 9 defines the opening through the frame 1 into the furnace and has its lateral edges welded to spaced front and back plates 12 and 13 which are of substantially U-shaped configuration. The water-containing enclosure of the frame is completed by a top plate 14, side plates 15, and bottom plates 16 which are welded to the outer edges of the front and back plates 12 and 13. When mounted in a furnace, the bottoms 16 of the legs 3 are received in recesses in the fore-plate or sill (not shown) mounted on the conventional breast-plate of the furnace.

When the frame is mounted in position in a furnace, the arch-bar 9 is continuously and directly exposed to the heat of the furnace. Upon removal of the frame from the furnace for repairs, the legs cool and their lower ends generally toe-in or warp in a direction toward each other to an extent that they cannot be re-inserted in the recesses provided therefor in the furnace supporting sill. Before the frame can be re-installed, it is necessary to straighten the frame legs so that they may be received 50 in the supporting sill recesses of the furnace. This is a troublesome and costly operation and increases the shut-down time of the furnace.

To eliminate warping or toe-in of the legs 3 in this manner, there is provided in accordance with the principles of this invention, heat-conducting means for reducing the working temperature of the arch bar-depending portions 11. As shown in Figs. 1 through 4, this heat-conducting means, in the preferred embodiment of the invention, comprises two rows of metal pins 17, preferably steel. The pins 17 are arranged at vertically-spaced intervals along substantially the entire length of the arch-bar portions 11 and have their ends integrally connected thereto by welding. The pins 17 extend in a horizontal direction into the path of cooling water flowing upwardly through the legs 3 over the internal surface of the arch-bar portions 11 and operate to transfer heat from the arch-bar to the cooling water. The pins being

in the path of movement of the cooling water, increase the efficiency of the heat transfer operation by imparting a degree of turbulence to the water flowing thereover. The arrangement of pins illustrated is effective to reduce the operating temperature of the arch-bar portions 11 and effects an overall reduction of the leg temperatures in operation. This has been found to eliminate warping and toe-in of the legs upon removal of the frame for furnace repairs with a consequent elimination of the troublesome and costly straightening operations heretofore required, and a reduction in furnace shut-down time by reason of such straightening operations.

In Figs. 5 through 7 there is shown a modified form of the invention for reducing the working temperatures of the legs 3. In this showing, the cooling pins corresponding to the pins 17 of Figs. 1 through 4 are designated by the numeral 17a. The pins 17a are of the same diameter but have a longer axial length so that they project farther into the path of movement of the water flowing through the legs. In addition to the pins 17a which are connected directly to the internal surfaces of the arch-bar portions 11, the back-plate 13 is provided with a vertical row of pins 18 which have their ends welded to the interior surface of the back-plate 13 and extend in a horizontal direction into the interior of the legs 3. The front plate 12 is provided with a similar row of metal pins 19. The pins 18 and 19 are preferably alternately arranged with respect to the pins 17a so that each vertical pair of adjacent pins 17a straddles one of the pins 18 or 19 as best shown in Fig. 6. The pins 18 and 19 conduct heat away from the back-plates 12 and 13 and effect a reduction in temperatures of the arch-bar in the area adjacent the welded connection of the back-plates 12 and 13 with the arch-bar depending portions 11. The transmission of heat away from the arch-bar connected front and back-plates 12 and 13 in turn effects a further reduction of the working temperature of the arch-bar 11.

The modification of the invention illustrated in Figs. 8, 9 and 10 utilizes steel plates 20 as the heat-conducting medium. The steel plates 20 extend vertically and centrally of the arch-bar depending portions 11 and have an integral welded connection therewith. The welded connection of each plate 20 extends along the entire length of the vertical edge thereof abutting against the internal surface of the depending portions 11. It is important that the plate 20 have an integral welded connection along its entire length in order that it will be effective to transfer heat in a proper manner since spot welding at spaced intervals along its length would not be satisfactory. Accordingly, it will be understood that the plate 20 to be effective must not only abut against the internal surface of the arch-bar depending portion 11 along its entire length, but additionally must have an integral welded connection along its entire length.

In Figs. 11 through 13, the reduction in working temperature is effected by steel plates 22 and 23 similar to the plate 20 shown in Figs. 8 through 10. The plates 22 and 23 respectively have similar integral welded connections along the entire length of one vertical edge thereof with the front and back-plates 12 and 13. The plates 22 and 23 transmit heat away from the front and back-plates in an area adjacent their welded connections with the arch-bar depending portions 11 in a manner similar to the pins 18 and 19 of the modification illustrated in Figs. 5 through 7.

From the foregoing, it will be apparent that the pins 17 or 17a as well as the plate 20, by reason of their integral connections with the depending portions 11 of the arch-bar, conduct heat away from the arch-bar and dissipate such heat into the cooling water flowing through the frame. In a similar manner, the pins 18 and 19 as well as the plates 22 and 23 effect a cooling action on the arch-bar although in this case it is necessary that the arch-bar

heat be transmitted first into the front and back plates 12 and 13. The cooling action in either case results in lowering the working temperature of the arch-bar depending portions, and, as a result, warping or toe-in of the legs 3 upon cooling after removal of the frame for furnace repairs is eliminated. Elimination of warping or toe-in of the furnace legs in this manner in turn eliminates the costly and time-consuming leg-strengthening operations heretofore required in conventional frame constructions.

While the above specification and accompanying drawings illustrate and explain several preferred embodiments of the invention, it will be understood that this is merely by way of illustration, and that various changes may be made therein within the contemplation of the invention and under the scope of the following claims.

I claim:

1. In a door frame for an open hearth furnace having an arch bar of inverted U-shape defining the furnace opening, front and rear plates respectively extending outwardly and upwardly from the laterally spaced edges of the arch bar and suitable connections between said plates providing connected hollow water receiving enclosures above and at each side of the arch bar, the combination of water inlets and outlets connected with the water receiving enclosures at each side of the arch bar providing continuous circulation of water therethrough, a plurality of metal heat conducting means secured to and spaced laterally and vertically of the inner face of the legs of said arch bar, said metal heat conducting means extending away from said arch bar across the path of circulation of water in said enclosures at each side of the arch bar imparting turbulence to the water and substantially uniform cooling of the face of the arch bar at the sides of the door frame opening.
2. The door frame as defined in claim 1 wherein the said metal heat conducting means extend to adjacent the outer and cooler face of the door frame into the cooler portion of the circulating water at the sides of the furnace door frame.
3. In a door frame for an open hearth furnace having an arch bar of inverted U-shaped defining the furnace opening, front and rear plates respectively extending outwardly and upwardly from the laterally spaced edges of the arch bar and suitable connections between said plates providing connected hollow water receiving enclosures above and at each side of the arch bar, the combination of water inlets and outlets connected with the water receiving enclosures at each side of the arch bar providing continuous circulation of water therethrough, a plurality of metal pins projecting inwardly from each of the vertically depending portions of said arch bar and at vertically spaced intervals therealong, and a plurality of metal pins projecting inwardly from said front and rear plates at vertically spaced intervals therealong and at points adjacent the integral connection of said plates with the depending portions of said arch bar.
